UNITED STATES PATENT OFFICE.

GREENLEAF A. WILBUR, OF SKOWHEGAN, MAINE, ASSIGNOR TO HIMSELF AND CHARLES HENRY WILBUR, OF SAME PLACE.

PENCIL CASE AND SHARPENER.

SPECIFICATION forming part of Letters Patent No. 326,697, dated September 22, 1885.

Application filed August 7, 1885. (No model.)

To all whom it may concern:

Be it known that I, GREENLEAF AUGUSTUS WILBUR, of Skowhegan, in the county of Somerset and State of Maine, have invented a new and Improved Pencil Case and Sharpener, of which the following is a full, clear, and exact description.

My invention relates to a simple, inexpensive, and effective device for incasing the sharp end of a pencil to protect its point, and also for sharpening the pencil, when required.

The invention consists in certain novel features of construction and combinations of parts of the combined pencil case and sharpener, all as hereinafter fully described and claimed.

Reference is to be had to the accompanying drawings, forming part of this specification, in which similar letters of reference indicate corresponding parts in all the figures.

Figure 1 is a perspective view of my improved pencil case and sharpener with the pencil in position in the case. Fig. 2 is a transverse section taken on the line $x-x$, Fig. 1; and Fig. 3 is an enlarged perspective view of the sharpener removed from the pencil-case.

The letter A indicates the pencil-case, which has a general tubular form, preferably round, and, as shown, is open at both ends, so that a rubber or eraser, B, may be placed in one end in the usual or any approved way, and so that a pencil, C, may be passed point first into the other end of the case, as shown clearly in Fig. 1.

The pencil-case A has a side slit or slot, D, at one end, said slot being enlarged at its base or inner portion, as at D', so that the pencil-sharpener E may be inserted in and be firmly held by the case A, as presently described.

The sharpener E has a tapering tubular form, and has an enlargement or rib, e, along one side, in which rib the knife or cutter F of the sharpener is held, so that its edge lies directly over a side slot, e', of the sharpener, which slot forms the throat through which the cuttings of the pencil pass from the knife to the outside of the pencil case and sharpener. The larger or outer end of the sharpener E snugly fits the inside of the pencil-case A, and the rib e of the sharpener gradually increases in height from the inner toward the outer end

of the sharpener, and at its outer end the rib projects beyond the end of the body of the sharpener, as at e², Fig. 3, so that when the sharpener E is placed small end first into the back end of the pencil-case A and is forced inward the rib e of the sharpener will pass through the slot D of the case, and until the forward end or part of the rib strikes the end d of the part D' of the slot D, and the opposite rounding side parts, a a, of the pencil-case—which is formed from suitable elastic metal—will clasp the opposite sides of the rib e of the sharpener, while the opposite shoulders, d' d', at the outer end of the enlargement D' of the slot D spring in, so as to lock back of the end of the body of the sharpener and behind the projection e² of the rib e of the sharpener. The sharpener thus will firmly be held to place in the slot D D' of the pencil-case and far enough toward the outer end of the case to allow the case to clasp the sharpened end of the pencil C back of its point, so as to protect the lead or point from breaking off, and yet so as to allow the pencil to be forcibly pushed in and turned against the edge of the knife F, to sharpen the pencil at any time required, as will readily be understood. By removing the rubber B from the case A a push-rod of any kind may be passed in through the outer end of the case to force the sharpener E bodily from the case to allow its knife F to be sharpened, or to insert a new sharpener in the case, or to allow a new case to be used with an old sharpener, as occasion may require.

The rubber B may not be used, and the sharpener-case A may then be made with an open or closed outer end, as may be preferred, and if the case be made with a closed end the sharpener may be forced from the case by pressure on the inner face of its projection e² at the outer end of the throat e' of the sharpener.

Having thus described my invention, what I claim as new, and desire to secure by Letters Patent, is—

1. A pencil case and sharpener comprising an elastic tubular case provided with a side slot at one end and a tapering tubular sharpener fitted with a knife or cutter and clamped in the case at the slot, substantially as herein set forth.
2. A pencil case and sharpener comprising an elastic tubular case, A, provided with a slot,

D D', and a tapering tubular sharpener, E, provided with a rib, e, having a throat, e', and a knife or cutter, F, set in said rib, and said sharpener held in place at the slot of the case A, substantially as herein set forth.

3. A pencil case and sharpener comprising an elastic tubular case, A, provided with a slot, D D', a tapering tubular sharpener, E, provided with a rib, e, having a throat, e', and a

projection, e², beyond the body of the sharpener, and said case A at the slot D D' having shoulders d' d', which lock under the body of the sharpener behind its projection e², substantially as herein set forth.

G. A. WILBUR.
